UNITED STATES PATENT OFFICE.

HENRY ALLES, OF SAN FRANCISCO, CALIFORNIA.

CURRENT MOTOR.

Application filed November 3, 1920. Serial No. 421,484.

To all whom it may concern:

Be it known that HENRY ALLES, a citizen of the United States, residing at city and county of San Francisco and State of California, has invented new and useful Improvements in Current Motors, of which the following is a specification.

This invention relates to a current motor, and particularly pertains to improvements in motors of the class shown in my Patent 1,014,930, granted January 16, 1912.

It is the principal object of the present invention to provide a current motor which may be readily positioned across a running stream in a manner to insure that the impact of the water against the blades thereof will be at desirable angles to the surface thereof, and that this impact shall be transferred into a rotary motion by which power can be produced.

The invention contemplates the use of parallel operating shafts mounted upon suitable pontoons or other floats in a stream of water, said shafts carrying sprockets upon which parallel chains are carried, the chains in turn being fitted with impulse blades adapted to extend into the water along the lower run of the chain, said sprockets being so designed as to permit the impulse blades to assume desired angular relation to the parallel chains.

The invention is illustrated by way of example in the accompanying drawings, in which:

Fig. 1 is a view in plan, showing the completely assembled current motor with parts broken away for the sake of convenience.

Fig. 2 is a view in end elevation showing the assembled current motor supported upon pontoons.

Fig. 3 is a view in side elevation showing the motor, and partially disclosing the arrangement of the impulse blades therein.

Fig. 4 is a fragmental view in perspective showing one of the chain links, and the manner of securing an impulse blade thereto.

Fig. 5 is a fragmental view in perspective showing a portion of the chain to which the impulse blades are connected.

Fig. 6 is a view in side elevation showing one of the sprocket wheels.

Fig. 7 is a view in elevation showing one of the flexible impulse blades.

Fig. 8 is a view in section and elevation disclosing one of the adjusting sleeves.

Referring more particularly to the drawings, 10 indicates a pontoon adapted to be floated within a river or other stream of running water, and anchored in position by cable 11, secured to an immovable object 12. 60 Members 13 and 14 indicate other pontoons disposed across the stream and a distance lower down, which pontoons are suitably secured together and are anchored to relatively fixed members 15 by cables 16. Members 12 and 15 are large 65 concrete blocks formed with eye bolts in their upper surfaces to which the cables may be secured. The pontoons are designed to be used to support a current motor. Parallel shafts 17 and 18 are provided, and are 70 mounted upon the pontoons. These shafts are carried within bearings 19, secured upon suitable frame work of the pontoons. In the adjustable form of the invention sprockets 20 and 21 are mounted on the shafts and 75 carry parallel sprocket chains 22 and 23. The construction of the sprockets is more clearly indicated in Figs. 3 and 7, where they will be seen to be built up from segments 24, which members are bolted together to 80 form a composite wheel.

The sprocket chains are formed with flat links 25, and specially designed links 26, which members are secured by chain pins 27. The links 26 have outwardly extending lugs 85 28 formed on one of their sides to receive a shackle member 29, and a channeled mounting 30 is secured to the shackle member, and is intended to receive the edge of impulse blade 31. These impulse blades are metal 90 or wood and are preferably flexible, so that they may be distorted and otherwise adapted to the adjustment on the machine. The opposite ends of the impulse blades are thus rigidly secured within the channel members 95 30, carried by the parallel chains, and when the machine is assembled the chains are so disposed as to support the blades at right angles thereto, and without flexure.

In order to permit disposal of the impulse blades at angles to a stream in which they are operating, while varying the relative angular positions of the sprocket wheels to each other on the shafts 17 and 18 without interrupting the driving action thereof, a 100 spider 32 is provided. This spider is rigidly secured to the shafts 17 and 18, at a point midway between the sprockets thereon. A spider comprises a plurality of radial arms 33, at the outer ends of which links 34 are 105 110

mounted. These links are universally jointed to brackets 35 carried on the inner face of the sprockets.

By referring to Fig. 1 it will be noted that 5 the members 34 are in pairs extending diametrically opposite from the arms upon which they are supported, and it will be evident that in the event the sprockets are rotated relative to each other they will be 10 moved toward or away from each other, depending upon the action. This movement of the sprockets toward and away from each other will also be accompanied by a relative rotation of the sprockets, one forwardly and 15 the other rearwardly as they are moved. This will act to shift the points of blade mountings along the chains and cause the impulse blades to be turned. The blades will at the same time be disposed at an angle to the 20 plane of the chains, and will thus make it possible to adjust the current motor to the direction of the flow of the stream.

Manipulation of the sprocket wheels 20 and 21 is brought about by operating mechanism comprising a hand-wheel 36, mounted 25 upon a shaft 37. This shaft extends horizontally through bearings 38, and is fitted with a bevel gear 39 adapted to mesh with a similar bevel gear 40 freely rotatable upon 30 shaft 17. Keyed to the gear 40, or formed integrally therewith is an enlarged spur gear 41, around which are arranged pinions 42 in mesh therewith. Pinions 42 are fixed upon the ends of screws 43, which extend 35 parallel to each other, and along opposite sides of the shaft 17. A shifting bar 44 is formed with threaded openings in its opposite ends through which the screws 43 extend. This bar also engages a shifting sleeve 45 in 40 a manner to prevent longitudinal movement of the sleeve without retarding its rotation. The sleeve is splined onto the shaft 17. This sleeve is fitted with a plurality of links 46, which connect with lever arms 47. The 45 lever arms are secured rigidly to radially extending shafts 48. These shafts have their mountings within a spider 49. This spider is held against longitudinal movement upon the shaft 17, but is free to rotate therewith. 50 The upper ends of the shafts 48 are bent to form crank arms 50, to which are secured connecting links 51. These links are provided with a universal connection to the crank arms 50, and also with universal connections 55 to brackets 52 extending outwardly from the sprocket wheels. It will thus be evident that by movement of the sleeve 45 the shafts 48 may be rotated and this movement in turn transmitted through the crank arms 50 and the connecting links 51, to draw the sprocket wheels toward or away from the spider.

By reference to Fig. 1 it will be seen that 60 each of the sprocket wheels is fitted with a shifting mechanism comprising the various

links and levers carried by the spider 49, and the operating sleeve 45. The mechanism upon the opposite end of shaft 17 is actuated by a transverse shaft 53, driven from the shaft 37 through beveled gears 54 and 55, 70 and transmitting motion to a shaft 37' through gears 56 and 57. Shaft 37' is parallel to the shaft 37, and is fitted with the bevel gear 39 in engagement with gear 40 upon the shaft. An operating mechanism 75 identical with that described for shaft 17 is used in connection with shaft 18. These two mechanisms are intended to operate in synchronism. This is brought about by a connecting chain 58, which is led around a sprocket 59 at one end and a sprocket 60 at its opposite end. The sprockets 59 and 60 are secured to vertical shafts 61 and 62 respectively, the opposite ends of which shafts are fitted with bevel gears 63 in mesh with 85 gears 64 upon the operating shafts 37. By this means it is possible to simultaneously adjust both of the sprocket wheels relative to the shafts upon which they are mounted.

In order to support the run of chain 90 against sagging a frame structure 65 is provided. This structure comprises uprights 66 extending vertically along the opposite sides of the chain and connected at their upper and lower ends by cross bar 67. This frame 95 carries rollers 68 adapted to be positioned beneath the upper and lower runs of the chain and support the same. Eye bolts 69 are mounted at the top of the frame and through these eye bolts tension cables 70 extend. The cables are secured to a cross frame member 71 of one of the pontoons and are led around idler sheaves 72, carried upon the opposite cross frame member 71. Both of the cables are then led to a tightening 105 drum 73. By this means a desired tension can be given to the cable, and the weight of the sagging chain supported accordingly.

In operation of the present invention, the current motor is assembled as shown in the 110 drawings, and may thereafter be disposed diagonally or straight across a stream of running water. When the proper diagonal position has been attained it is desirable to adjust the impulse blades 31 so that they 115 will stand at angles to the direction of flow of the water, so that force of the stream throughout its width may be utilized in driving the motor. This is brought about by rotation of the hand wheel 36. The sleeves on 120 each shaft are moved toward each other, thus acting through the spiders 49 and the attendant levers to shift the sprocket wheels inwardly, and to produce a like movement upon each side of the spider 32. As this 125 shifting movement takes place the link members 34 upon the ends of arms 33 will rotate around the arms 33, one end moving forward and the other moving rearwardly. This will act to rotate one of the sprockets in one direc- 130

tion around its shaft, and the other sprocket in a reverse direction around the same shaft. The result will be that one chain will be advanced and the other one retracted, thus placing the impulse blades 31 at an angle to the sprocket chains. It will be understood that like advancement will take place on both of the shafts, and that by proper manipulation of the hand wheel the impulse blades may be disposed with their faces directly at right angles to the stream of water if desired. When this arrangement is brought about it will be recognized that the blades will be arranged substantially across the stream with one blade in the rear of the next succeeding blade and off-set therefrom, so that each of the blades will be struck by a portion of the stream without obstruction from the blade in front thereof.

20 Due to the offset formation of link 29' the blades may easily swing while the chains pass around the sprockets, this preventing damage to the blades or binding of the chain.

25 It will thus be seen that by providing a current motor as here disclosed, and disposing it with the impulse blades of its lower run of chain within a stream of water and with the surfaces and blades at angles 30 to said flow, a maximum amount of power may be obtained from the flowing stream and converted into useful rotary movement through the shafts 17 and 18, at the same time insuring that under varying conditions and requirements the current motor 35 may be adjusted to efficiently operate.

While I have shown the preferred form 40 of my invention, it will be understood that various changes in the combination, construction and arrangement of parts may be made by those skilled in the art, without departing from the spirit of the invention as claimed.

Having thus described my invention, what 45 I claim and desire to secure by Letters Patent is:

1. A current motor comprising a plurality of impulse blades, parallel chains to which the opposite ends of said blades are secured, sprocket wheels over which said 50 chains pass, parallel shafts upon which the sprocket wheels are freely mounted, a driving spider interposed between the sprocket wheels on each of said shafts, and articulate 55 means for imparting movement from said sprockets to said spider.

2. A current motor comprising a plurality of impulse blades, parallel chains to which the opposite ends of said blades are secured, sprocket wheels over which said 60 chains pass, parallel shafts upon which the sprocket wheels are freely mounted, a driving spider interposed between the sprocket wheels on each of said shafts, and articulate

means for imparting movement to said 65 sprockets from said spider, and means for longitudinally moving said sprockets along their respective shafts.

3. A current motor comprising a pair of parallel rotatable shafts, a pair of sprocket 70 wheels carried by each of said shafts, sprocket chains led around the complementary sprocket wheels on the two shafts, impulse blades secured to the sprocket chains and disposed there between, means carried 75 by the shaft between the sprocket wheels for imparting motion to the separate sprockets on each shaft in opposite directions, and means for imparting motion to the shafts irrespective of the relative positions of the sprockets.

4. A current motor comprising a pair of parallel shafts, a driving spider secured midway the length of each shaft, a pair of sprockets freely mounted upon the shafts at 85 the opposite sides of the spiders, articulate traveling connections between the sprockets and the spiders, sprocket chains leading over the complementary sprockets of the two shaft impulse blades secured by their 90 opposite ends to the adjacent faces of the chains, and means for changing the relative relation of the sprocket chains to each other, in order to change the angular position of the blades and without disturbing the delivery of power from the chains to the 95 shafts.

5. A current motor comprising a pair of rotatable shafts, spaced sprockets mounted thereon, for longitudinal movement and having parallel chains trained thereover, impulse blades disposed between the chains, and means interposed between the sprocket 100 wheels for imparting reverse rotary motion to the sprocket wheels with relation to each other when the sprocket wheels are moved longitudinally of the shaft.

6. A current motor comprising spaced pontoons, a rotary shaft on each pontoon in parallel relation, a pair of interspaced 110 sprocket wheels mounted on each shaft for rotary and longitudinal motion and a parallel chain trained over one sprocket on each of the shafts, impulse blades secured to the parallel chains and lying between the same 115 and means on each shaft between the sprocket wheels for imparting reverse rotary motion thereto with relation to each other when the sprocket wheels are moved longitudinally of the shafts, to adjust the angular position of the impulse blades.

7. A current motor comprising a pair of parallel spaced chains, a series of flexible impulse blades connected at their opposite ends to and between said chains, sprockets 125 upon which said chains are mounted, shafts upon which they are free to rotate and move longitudinally, means for simultaneously

adjusting the sprockets circumferentially and longitudinally of their shafts, and moving the sprockets toward and away from each other, and articulate traveling connections between the sprockets and the shafts whereby movement may be imparted from the sprockets to the shafts, irrespective of their adjusted positions.

8. A current motor comprising a pair of 10 rotatable shafts, a driving spider secured intermediate the ends of each of said shafts, articulate driving means secured at the outer ends of said spider arms, said means extending in opposite directions from each 15 other and parallel to the shafts, sprocket wheels, one of which is articulately secured to each of said driving connections, said wheels being freely rotatable upon the shafts and longitudinally movable relative thereto, 20 sprocket chains leading around complementary sprockets on the two shafts and disposed in parallel relation to each other, flexible impulse blades disposed between chains and connected by their opposite ends thereto, 25 and means for simultaneously adjusting all of the sprocket wheels axially and rotatably upon their shafts whereby the blades will

be flexed to assume angular positions relative to the longitudinal axis of the shafts.

9. A current motor comprising a pair of 30 rotatable shafts, a driving spider secured intermediate the ends of each of said shafts, articulate driving means secured at the outer ends of said spider arms, said means extending in opposite directions from each 35 other and parallel to the shafts, sprocket wheels, one of which is articulately secured to each of said driving connections, said wheels being freely rotatable upon the shafts and longitudinally movable relative thereto, 40 sprocket chains leading around complementary sprockets on the two shafts and disposed in parallel relation to each other, flexible impulse blades disposed between chains and connected by their opposite ends thereto 45 and means for simultaneously adjusting all of the sprocket wheels axially and rotatably upon their shafts whereby the blades will be flexed to assume angular positions relative to the longitudinal axis of the shafts, and 50 adjustable means for supporting the chains at points intermediate their sprockets.

HENRY ALLES.
